UNITED STATES PATENT OFFICE.

CHARLES G. FREDMAN, OF BROOKLYN, NEW YORK.

MILLING-MACHINE.

1,285,667.

Specification of Letters Patent. Patented Nov. 26, 1918.

Application filed January 14, 1918. Serial No. 211,764.

To all whom it may concern:

Be it known that I, CHARLES G. FREDMAN, a citizen of the United States, and residing at Brooklyn, in the county of Kings 5 and State of New York, have invented certain new and useful Improvements in Milling-Machines, of which the following is a specification, such as will enable those skilled in the art to which it appertains to make and 10 use the same.

This invention relates to what are known as milling machines, and the object thereof is to improve a machine of this class so as to facilitate the working thereof in all classes 15 of work for which such machines are designed or adapted, and with this object in view the invention consists in the method of operating a machine of the class specified, as hereinafter described and in the construction 20 by which said method is carried into effect.

The invention is fully disclosed in the following specification, of which the accompanying drawings form a part, in which the separate parts of my improvement are designated by suitable reference characters in each of the views, and in which:—

Figure 1 is a front view of a milling machine constructed according to my invention, the base portion of the machine, including 30 the framework being only indicated in dotted lines and the improved construction described and claimed herein being shown in full lines;

Fig. 2 a side view of the construction as 35 shown in Fig. 1;

Fig. 3 a front sectional view of the machine as made by me, or the head portion of said machine, said view being taken on the line 3—3 of Fig. 6;

Fig. 4 a section on the line 4—4 of Fig. 3;

Fig. 5 a section on the line 5—5 of Fig. 3;

Fig. 6 a section on the line 6—6 of Fig. 2;

Fig. 7 a section on the line 7—7 of Fig. 6;

Fig. 8 a section on the line 8—8 of Fig. 6;

Fig. 9 a section on the line 9—9 of Fig. 7;

Figs. 10 and 11 diagrammatic side views of the cutting tool which I employ and indicating the method of operating said tool;

Figs. 12 and 13 diagrammatic detail front 50 views of the construction shown in Figs. 10 and 11; and,

Fig. 14 a view similar to Fig. 3 but showing only a part of the construction and indicating a different use of the machine.

55 In the drawing forming part of this specification, reference being made to Figs. 1

and 2, I have indicated at 20 the base of the framework of a machine of the class specified, and at 21 the back upright or head portion of said frame work, and at 22 I have indicated the main vertically movable table of a machine of the class specified, and at 23 and 24 the movable and adjustable tables with which machines of this class are usually provided, and at this time, I desire to say 60 that my invention relates only to the upper structure of the machine, or that part thereof above the tables 23 and 24, or that part of the machine which involves and relates to the operation of the tool or tools employed, and 65 in the practice of my invention I provide a supplemental frame 25 which is bolted or otherwise secured to the back frame member 21, and the supplemental frame 25 consists of the following parts, namely, a base member 70 26, a back member 27, a short side member 28, a longer side member 29 and a central member 30.

The top central portion of the side member 28 is provided with a bearing 31, and 75 the top central portion of the central member 30 is provided with a bearing 32, and centrally of the longer side member 29 is a similar bearing 33, and rotatably mounted in the bearings 31, 32 and 33 is a main drive 80 shaft 34 which may be driven in any desired manner by a pulley mounted on the end thereof, said pulley or the means for driving said shaft being not shown.

A supplemental drive shaft 35 is mounted 90 below the main drive shaft 34 and forwardly thereof in bearings 36 and 37 integral with, or forming a part of the longer side member 29, and the base member 26 respectively, as clearly indicated in Figs. 1 and 4 of the 95 drawing.

Mounted on the outer end of the supplemental drive shaft 35 is a cone or stepped pulley 38 and mounted on the inner end of said shaft is a worm 39 adapted to drive a 100 worm gear 40 secured to a stub shaft 41 rotatably mounted in the base 26 and in a supplemental bearing member 42 integral with the back 27 of the frame 25.

Secured to the upper end of the stub shaft 105 41 is a beveled pinion 43 adapted to operate in connection with beveled gears 44 and 45 rotatably mounted on the main drive shaft 34 between the frame members 29 and 30, and secured to said shaft between said bevelled gears is a clutch member 46 having a central annular recess 47, and the opposite

sides of which are provided with clutch heads 48 and 49 adapted to operate in connection with clutch faces 50 and 51 on the inner sides of the beveled gears 44 and 45 respectively.

A cross bar 52 is secured to the face of the frame members 29 and 30 below the center of the main drive shaft 34, as clearly shown in Figs. 1 and 4, and pivoted centrally of said cross bar is a clutch operating lever 53, the inner end of which is provided with a yoke-shaped head 54 in the ends of which are mounted pins 55, the inner ends of which are provided with anti-friction rollers 56 which are adapted to operate in the annular recess 47 in the clutch member, as clearly shown in Figs. 3 and 4. The outer end of the lever 53 is provided with a handle portion 57 by means of which said lever may be manipulated to move the clutch member 46 into engagement with either of the beveled gears 44 or 45, as hereinafter described.

Secured to the main drive shaft 34 between the frame members 28 and 30 is an eccentric gear 58 which operates in connection with another and similar eccentric gear 59 secured to a rotary power shaft 60 mounted in the top portion of the frame 30 forwardly of the main drive shaft 34 and in bearings 61 and 62 in the frame members 28 and 30 respectively. One end portion of the shaft 60 is provided with a rectangular head 63 in which is mounted a threaded shaft 64 supported in end plates 65 and 66, and secured to one end portion of the threaded shaft 64 is a milled head 67 by means of which said shaft may be rotated to move a block 68 longitudinally thereof. The block 68 has a tongue and groove connection with the head 63, as clearly shown in Fig. 9, and a gib 69 is employed, as in other machines of this class, said gib being held in place by set screws 70 shown in Figs. 1 and 9. The block 68 is provided with a stud 71 having a reduced threaded portion 72 and a bearing sleeve 73 is mounted on the stud 71 as shown in Figs. 3 and 9, and mounted on said stud and said sleeve is a main power rack 74 held in place by a nut 75 mounted on the reduced threaded portion 72.

The frame members 28 and 30 are provided, forwardly of and beneath the bearings 31 and 32, with other bearings 76 and 77 in which is mounted an oscillatory stub shaft 78 provided at one end with a rectangular cross head 79 bolted to an oscillating head 80, as clearly shown in Figs. 1 and 6.

The main power rack 74 has a tongue and groove connection with the oscillating head 80, as shown at 81 in Fig. 6, and a gib 82 is employed in the usual manner, said gib being held in place by set screws 83 one of which is shown in said figure. Mounted in

the head 80 forwardly of the main power rack 74 is a supplemental driven rack and tool holder 84 which also has a tongue and groove connection with said head as shown at 85, and a gib 86 is also employed in connection with the rack 84, said gib being held in place by set screws 87, and by bolts 88 passed therethrough. The gib 86 is provided with elongated slots 89 where said bolts pass through the same as clearly shown in Fig. 8.

The supplemental rack 84 is provided at the top thereof with an enlarged head portion 90 having a bearing extension 91 at one side thereof, and a forwardly directed bearing extension 92. The front face of said rack is provided with a rectangular aperture or recess 93 which extends from the base of the forwardly directed bearing 92 to the bottom of said rack, and adjustably mounted in the bottom portion of said aperture is a tool clamping plate 94 provided with a tool aperture 95 having a beveled rib 96 in the back wall thereof, and a tool 97 is adapted to be mounted in the aperture 95 and held therein by the rib 96 which enters a corresponding recess 98 in the shank of the tool, and a transverse plate 99 is bolted to the face of the supplemental rack 84, and this plate serves to hold the tool 97 in firm connection with said rack.

Rotatably mounted in a central web portion 100 of the head 80 are two vertically arranged shafts 101 and 102 on which are mounted gears 103 and 104 respectively, and said gears are adapted to operate in connection with the gear faces 105 and 106 on the racks 74 and 84 respectively. The end portions of the shaft 102 are mounted in rectangular sleeve bearings 107, the top faces of which are beveled inwardly as shown at 108 and wedge-shaped bolts 109 are mounted above the sleeve bearings 107 and are adapted to be forced outwardly by nuts 110 mounted on the outer ends thereof, and this construction serves to hold the shaft 102 in the proper or any desired position, as will be readily understood. The central web portion 100 is provided above the gear 103 with a vertical aperture 111 through which the nut 75 on the end of said stud 71 is adapted to pass in the vertical movement of the rack 74, as will be readily understood on a consideration of Fig. 3 of the drawing.

Adjustably mounted in the aperture 93 in the supplemental rack 84 is a tool supporting block 112, consisting of a back rectangular portion 113 which is movable in said aperture, and one side edge of which is provided with a rack construction 114, and said portion 113 is held within the aperture 93 in any desired position of adjustment of the block 112 by clamp plates 115 secured to the opposite faces of the rack 84, as clearly indicated in Fig. 6 of the drawing.

One of the clamp plates 115 is provided, approximately, centrally thereof with a boss 116 in which is mounted a shaft 117 to the inner end of which is secured a pinion 118, 5 which operates in connection with the rack construction 114 at one side of the rectangular portion 113 of the block 112, and secured to the front end of the shaft 117 is a crank 119 by means of which the shaft 117 may be 10 rotated to adjust the tool supporting block 112 vertically in the aperture 93, in which operation the bolts 120 for holding the clamp plates 115 in place are loosened to permit of said adjustment, after which said 15 bolts are tightened and this serves to hold said block in firm connection with the block 84.

The front portion of the tool supporting block 112 is provided with an annular head 121 in which is mounted a bearing sleeve 122 within which is rotatably mounted a tubular shaft 123, the lower end of which is provided with a central tapered aperture 124 adapted to receive a shank 125 of a tool 20 supporting chuck 126. Connected with the top of the shank 125 is a rod 127 which passes through the top portion 128 of the tubular shaft 123 and is provided at its upper end with a nut 129 which serves to hold 25 the tool supporting chuck 126 in proper position, as will be readily understood.

The tubular shaft 123 is held against vertical movement in the block 112 by a flanged base portion 130 and a detachable nut 131 30 mounted above the sleeve bearing 122 as clearly shown in Figs. 3 and 14. The tubular shaft 123 is vertically movable through a sleeve bearing 132 mounted in the forwardly directed bearing 92 on the top of 35 the rack 84, and secured to and movable longitudinally of the top portion of the shaft 123 is a spiral gear 133 which meshes with a similar gear 134 mounted on the end portion of a shaft 135 supported in the side 40 bearing extension 91 on the top of the rack 84.

The longer side frame member 29 extends above the top of the back member 27 of the frame 25 and is provided in the top portion 50 thereof with a bearing 136 having a supplemental power shaft 137, and bolted to said side member 29 below the bearing 136 is a bracket frame 138, comprising a front plate 139, a cylindrical web portion 140 and a 55 back cross head 141. The top of the cross head 141 is provided with a bearing 142 similar to the bearing 136 and adapted to support the shaft 137, while the bottom portion of the cross head 141 is provided with a bearing 60 143 which serves to support the rearwardly directed portion of the main drive shaft 34.

Mounted on the shaft 137 between the bearings 136 and 142 is a cone or stepped pulley 144 which is in vertical alinement 65 with the pulley 38, and is adapted to oper-

ate in connection therewith by a belt passed therearound, as will be readily understood, but said belt is not shown in the drawing, and it will be also understood that said pulleys may be driven independently by belts 70 passed therearound from other pulleys not shown, driven in any desired manner.

A link shaft 145 composed of a plurality of parts secured together is connected with the shaft 137 by a universal joint 146 at one end 75 of said link shaft and the other end of said link shaft is connected with the shaft 135 by a universal joint 147, but it will be understood that the detail construction of the link shaft 145 and its connection with the shafts 80 135 and 137 may be made in any desired manner, and is commonly known in this art, and for this reason such details have not been shown, said shaft being adapted to rotate the spiral gear 134 on the end of the shaft 85 135 which in turn rotates the spiral gear 133 to rotate the tubular shaft 123 to rotate the tool supported in the clutch 126 as will be readily understood.

One side of the rectangular head 63 on the 90 end of the shaft 60 is provided with a scale from zero to two inches, as indicated at 148 in Fig. 1, which scale extends from the center of the shaft 60 upwardly or outwardly two inches as shown, but the extent of this scale 95 will be determined by the size and construction of the head 63 as will be readily understood. The head portion of the rack 74 is provided with a scale mark 149 which is in line with or designates the center of the stud 100 71 on the block 68, which mark is adapted to register with the scale 148 on the head 63 and by manipulating the milled nut 67 on the end of the threaded shaft 64, said block 68 may be moved vertically in said head to 105 bring the mark 149 into any desired position along the scale 148. The position of the head shown in Fig. 1 is at the extent of its movement on the scale 148.

In the construction shown, each of the 110 bearings 31, 32, 33, 36, 42, 61, 62, 76, 77, 91, 136, 142 and 143 are provided with detachable caps as clearly shown in the drawing, whereby the shafts mounted therein may be easily set in place and whereby new sleeve 115 bearings may be provided whenever desired.

In Fig. 14 I have shown the operative parts of my improved machine in a different position from that shown in Figs. 1 to 13 inclusive, in which position of said parts the 120 rack bars 74, and 84 are brought into neutral position, or the center of the stud 71 is brought in line with the center of the shaft 60, whereby the rotation of the shaft 60 will not move said racks vertically in the head 80 125 as in the construction shown in Figs. 1 to 13 inclusive, and the tool 97 is detached from the bottom portion of the rack 84. The tool supporting block 112 is shown adjusted to the bottom portion of the rack 84 in said 130

figure, and a rotary milling tool 150 of the usual form and construction is connected with the chuck 126, it being understood that said block 112 is moved downwardly from the position shown in Fig. 3 to that shown in Fig. 14 by the operation of the crank 119, as hereinbefore described.

In the position of the parts of my machine, as shown in Fig. 14 the same will operate as an ordinary milling machine, and in practice when it is desired to cut into a workpiece 151 to any great extent said workpiece is placed upon the table members 23 and 24, and secured thereto in the usual manner, and adjusted to bring said workpiece in line with the milling tool 150, after which said tool is rotated by applying power to the shafts 137, 145 and 135, as will be readily understood, and with this tool and by manipulating the tables 23 and 24, the workpiece 151 may be roughed out as indicated at 152 in Fig. 14 in the usual manner, after which the block 112 may again be raised into the position shown in Fig. 3 and the tool 150 detached from the clutch 126 and the finishing cuts on the workpiece 151 may be accomplished in the following manner.

The operation of the main working part of my improved machine will be readily understood from the foregoing description when taken in connection with the accompanying drawings and the following statement thereof. The workpiece 151 after being roughed out, as hereinbefore described, is brought into line with the tool 97 supported in the rack 84 by manipulating the tables 23 and 24, and said tables, including the main bed plate 22 are further manipulated to bring the top face 153 of said workpiece six inches from the mark 154 on the face of the head 80, as indicated in Fig. 2, which mark indicates the center line of the shaft 78. The relative centers of the shafts 60 and 78 are six inches apart as indicated in Figs. 12 and 13 of the drawings. The next step is to adjust the block 68 vertically in the head 63 to bring the mark 149 to the desired position on the scale 148 to perform the next cut on the roughed workpiece which will be determined by the operator of the machine, and in performing the finishing cut, the block 68 is adjusted to bring the mark 149 to the indication of two inches on the scale 148, and in Figs. 10 to 13 inclusive, I have indicated the operation of the tool 98 and the parts with which it is connected, or by which it is operated, through the finishing operation of said tool, or its operation in performing the finishing cut. In Figs. 10 and 12 I have shown in full lines the tool 97 in its highest position and in dotted lines I have indicated the position of said tool at one-quarter revolution of the shaft 60, while in Figs. 11 and 13, I have indicated in full lines the position said tool as-

sumes at one-half of a revolution of the shaft 60, and have indicated in dotted lines the position said tool assumes on a three-quarter revolution of the shaft 60, the finished cut or aperture in the workpiece 151 being indicated in full and dotted lines in Fig. 11 at 155, and it will be noted that the full line position of the tool 97 is shown in Figs. 1, 2 and 3, while the parts for operating said tool shown in Figs. 1 to 9 inclusive are in a corresponding position, the eccentric gears 58 and 59 being driven by the shaft 34 direct.

In the foregoing description I have stated that the top face 153 of the workpiece 151 is located six inches from the center of the shaft 78 in performing the finishing cuts, or operations in said workpiece, but it must also be understood that the cutting face or area of the tool 97 when secured in the rack 84 and when said rack is in its neutral position as shown in Fig. 14, the distance between said cutting face on said tool and the center of the shaft 78 must also be six inches, and in Fig. 3 of the drawing it will be noted that the tool clamping plate 94 is provided in its rear face with notches or recesses adapted to receive an angular projection 84^a on the rack 84 within the aperture 93, whereby said tool clamping plate may be adjusted vertically in the rack 84.

For the purpose of description the top face 153 of the workpiece will be regarded as the predetermined working plane, or the plane through which the tool 97 passes to perform a semi-circular cut in said workpiece, and while the said plane is located at the face of the workpiece, as hereinbefore described, it will be understood that said plane may be located anywhere from the base portion to the top face of said workpiece ranging parallel with the supporting table or bed plate, and this line is preferably scribed on said workpiece by the operator of the machine and the foregoing steps followed exactly in order to perform the desired cut in the workpiece, and in this connection I desire to say that regardless of where the predetermined plane is located on the workpiece the tool, or the cutting face thereof will always pass through said plane in a semi-circular path.

When it is desired to decrease the speed at which the tool 97 is operated, the lever 53 may be manipulated to move the clutch 120 member 46 into engagement with the face of either of the beveled gears 44 or 45, in which operation the means for driving the shaft 34 is shut off, or disconnected, and said shaft is driven through the shaft 35, the worm 39, the worm gear 40, the pinion 43 and either of the beveled gears 44 or 45, as will be readily understood.

The object of driving the shaft 60 by means of the eccentric gears 58 and 59 is to

govern the movement of the tool 97, or the speed at which it travels in the different positions thereof, and in the construction of eccentric gears as shown, said tool will be 5 driven slowly, while performing its cutting operation, or while operating upon the workpiece 151, but will travel very quickly in its idle movement, or while bringing it from its last cutting position to its first cutting 10 position. It must also be understood that in cutting one radius which is common throughout the length or width of the workpiece, said workpiece is fed in a horizontal plane in the usual manner in cutting 15 elongated recesses in workpieces of various kinds and classes, but it will be understood that with my improved machine any desired form of recesses or milling operations may be performed in a workpiece that can be 20 formed on milling machines, as now constructed, or that are now in use and many operations that cannot be performed on the present machines may be accomplished on my improved machine by reason of the construction 25 thereof, or the means employed for operating the tool 97. It must be also understood that elliptical or other irregular shapes or forms of apertures may be milled into a workpiece by moving the bed plate 22 30 vertically to reduce the distance between the face 153 of the workpiece and the center of the shaft 78, or the mark 154 indicated in Fig. 2.

The method of operating the tool 97 which 35 may be of any preferred form and construction, as herein shown and described, moves said tool through a circular or approximately circular path, and the cutting face of the tool moves or operates in the workpiece 40 through an arc-shaped path, as clearly illustrated in Figs. 10 and 11 of the drawing, and while I have described the tool 150 as being rotated to rough out a workpiece 151, it will be understood that on certain classes 45 of work a tool of this character may be employed and rotated as herein described, in which operation thereof the same may be moved through a circular or approximately circular path, or the cutting face thereof 50 moved through the workpiece in an arc-shaped path, which operation may be accomplished by simply detaching the tool 97 from the rack 84 and moving the head 112 into the position shown in Fig. 14, while the 55 racks 74 and 84 remain in the position shown in Figs. 1, 2, and 3, and the operation of the machine, as hereinbefore described for operating the tool 97, as indicated in Figs. 10 to 13 inclusive, will operate the tool 150 60 in the same manner, while said tool is rotated, this combined movement being accomplished by connecting the pulleys 38 and 144 with a belt, as hereinbefore described. It will also be understood that the tool 150 65 may be rotated when in use as shown in Fig.

14, in two ways first by driving the shaft 137 direct by any suitable motor power, or said shaft may be driven through the shaft 34, the beveled gears 44 and 45, the beveled pinion 43, the worm gear 40 and worm 39, 70 the pulleys 38 and the pulleys 144, and while I have shown certain details of construction for carrying my invention into effect and have designated a predetermined dimension between the centers of the shafts 60 and 78, 75 and the center of the shaft 78 and the face 153 of the workpiece, it will be understood that these dimensions may be increased or decreased provided that they are of the same relative proportion, the dimensions indicated being what may be termed the happy medium or those most suitable for the average work, and other changes in and modifications of the details of construction herein shown and described may be made, within 80 the scope of the appended claims, without departing from the spirit of my invention or sacrificing its advantages, and means other than those herein described may be employed for operating the tubular tool 90 shaft 123.

Having fully described my invention, what I claim as new and desire to secure by Letters Patent, is:—

1. In a milling machine of the class described, a tool holder, means for giving said tool holder a combined lateral and vertical oscillatory movement, a supplemental tool holder, means for rotating said supplemental tool holder, and means whereby said supplemental tool holder may be given a combined lateral and vertical oscillatory movement in the operation thereof. 95

2. In a machine of the class described, a frame, a drive shaft mounted therein, a power shaft driven by said drive shaft, a cross head connected with said power shaft, a main drive rack adjustably mounted in said cross head, a supplemental driven rack geared in connection with said main drive rack, an oscillatory shaft mounted in said frame the center of which is a predetermined distance from the center of the power shaft, an oscillatory head connected with said oscillatory shaft and through which said racks are adapted to pass, and means for supporting a tool in connection with said supplemental driven rack. 105

3. In a machine of the class described, a frame, a drive shaft mounted therein, a power shaft driven by said main drive shaft, a cross head connected with said power shaft, a main drive rack adjustably mounted in said cross head, a supplemental driven rack geared in connection with said main drive rack, an oscillatory shaft mounted in said frame the center of which is a predetermined distance from the center of the power shaft, an oscillatory head connected with said oscillatory shaft and 110 115 120 125 130

through which said racks are adapted to pass, means for supporting a tool in said supplemental driven rack, and means on the main drive shaft for reducing the speed 5 at which the power shaft is driven and the direction which said shaft is driven.

4. In a machine of the class described, a frame, a drive shaft mounted therein, a power shaft driven by said main drive shaft, a cross head connected with said power shaft, a main drive rack adjustably mounted in said cross head, a supplemental driven rack geared in connection with said main drive rack, an oscillatory shaft 10 mounted in said frame the center of which is a predetermined distance from the center of the power shaft, an oscillatory head connected with said oscillatory shaft and through which said racks are adapted to 15 pass, means for supporting a tool in said supplemental driven rack, means on the main drive shaft for reducing the speed at which the power shaft is driven and the direction which said shaft is driven, a supplemental rotary tool holder mounted in said supplemental rack, and means for driving 20 said supplemental tool holder.

5. In a machine of the class described, a frame, a main drive shaft mounted therein, a supplemental drive shaft mounted beneath said main drive shaft and geared in connection therewith through a clutch member, a power shaft mounted in said frame and geared in connection with the 25 main drive shaft, said power shaft being provided at one end with a cross head, a main drive rack adjustably mounted in said cross head, an oscillatory shaft mounted in said frame, an oscillating head secured to 30 one end of said last named shaft and through which said main drive rack is adapted to move, a supplemental driven rack movably mounted in said oscillating head and geared in connection with said 35 main drive rack, said supplemental driven rack being provided at one end with an enlarged head portion, and means for adjustably supporting a tool in the other end thereof.

40 6. In a machine of the class described, a frame, a main drive shaft mounted therein, a supplemental drive shaft mounted beneath said main drive shaft and geared in connection therewith through a clutch member, a power shaft mounted in said frame and geared in connection with the 45 main drive shaft, said supplemental driven rack being provided at one end with an enlarged head portion, and means for adjustably supporting a tool in the other end thereof.

50 7. In a machine of the class described, a frame, a main drive shaft mounted therein, a supplemental drive shaft mounted beneath said main drive shaft and geared in connection therewith through a clutch member, a power shaft mounted in said frame and geared in connection with the 55 main drive shaft, said power shaft being provided at one end with a cross head, a main drive rack adjustably mounted in said cross 60 head, an oscillatory shaft mounted in said frame, an oscillating head secured to one end of said last named shaft and through which said main drive rack is adapted to move, a supplemental driven rack movably mounted in said oscillating head and geared 65 in connection with said main drive rack.

in connection with said main drive rack, said supplemental driven rack being provided at one end with an enlarged head portion, means for adjustably supporting a tool in the other end thereof, a supplemental rotary tool holder adjustably mounted in said supplemental rack, and means for driving said rotary tool holder.

7. In a machine of the class described, a frame, a main drive shaft mounted therein, a supplemental drive shaft mounted beneath said main drive shaft and geared in connection therewith through a clutch member, a power shaft mounted in said frame and geared in connection with the main drive 70 shaft through eccentric gears, said power shaft being provided at one end with a cross head, a main drive rack adjustably mounted in said cross head, an oscillatory shaft mounted in said frame, an oscillating head secured to one end of said last named shaft and through which said main drive rack is 75 adapted to move, a supplemental driven rack movably mounted in said oscillating head and geared in connection with said main drive shaft, said supplemental driven rack being provided at one end with an enlarged head portion, and means for adjustably supporting a tool in the other end thereof.

8. In a machine of the class described, a frame, a main drive shaft mounted therein, a supplemental drive shaft mounted in said frame, beveled gears rotatably mounted on said main drive shaft and geared in connection with said supplemental drive shaft, a clutch member in operative connection with said beveled gears, means for operating said clutch member, a power shaft mounted in said frame, eccentric gears for gearing said power shaft and the main drive shaft together, one end of the power shaft being provided with a cross head, a main drive rack adjustably mounted in said cross head, an oscillatory shaft mounted in the frame, one end of said shaft being provided with an oscillating head through which said main drive rack is adapted to pass, a supplemental driven rack movably mounted in said oscillating head, means for gearing said racks together, and an adjustable tool holder 100 mounted in said supplemental rack.

9. In a machine of the class described, a frame, a main drive shaft mounted therein, a supplemental drive shaft mounted in said frame, beveled gears rotatably mounted on 105 said main drive shaft and geared in connection with said supplemental drive shaft, a clutch member in operative connection with said beveled gears, means for operating said clutch member, a power shaft mounted in 110 said frame, eccentric gears for gearing said power shaft and the main drive shaft together, one end of the power shaft being provided with a cross head, a main drive rack adjustably mounted in said cross head, 115

an oscillatory shaft mounted in the frame, one end of said shaft being provided with an oscillating head through which said main drive rack is adapted to pass, a supplemental driven rack movably mounted in said oscillating head, means for gearing said racks together, an adjustable tool holder mounted in said supplemental rack, means adjustably mounted in the supplemental rack for supporting a rotary tool holder, and means for driving said rotary tool holder.

10. In a machine of the class described, a frame, a drive shaft mounted therein, a power shaft geared in connection with said drive shaft, a rack construction adjustably connected with one end portion of said power shaft, an oscillating guide for said rack construction, and means for adjustably connecting a tool holder with said rack construction.

15. In a machine of the class described, a frame, a drive shaft mounted therein, a power shaft geared in connection with said drive shaft, a rack construction adjustably connected with one end portion of said power shaft, an oscillating guide for said rack construction, means for adjustably connecting a tool holder with said rack construction, and means on said drive shaft for varying the speed at which the power shaft is driven 30 and for governing the direction at which said shaft is driven.

20. In a machine of the class described, a frame, a drive shaft mounted therein, a power shaft geared in connection with said drive shaft, a rack construction adjustably connected with one end portion of said power shaft, an oscillating guide for said rack construction, means for adjustably connecting a tool holder with said rack construction, and a supplemental tool holder adjustably connected with said rack construction.

25. In a machine of the class described, a frame, a drive shaft mounted therein, a power shaft geared in connection with said drive shaft, a rack construction adjustably connected with one end portion of said power shaft, an oscillating guide for said rack construction, means for adjustably connecting a tool holder with said rack construction, a supplemental tool holder adjustably connected with said rack construction, and means for operating said supplemental tool holder.

30. In a machine of the class described, a frame, a drive shaft mounted therein, a power shaft geared in connection with said drive shaft, a rack construction adjustably connected with one end portion of said power shaft, an oscillating guide for said rack construction, means for adjustably connecting a tool holder with said rack construction, a supplemental tool holder adjustably connected with said rack construction, and means involving said rack con-

struction for operating said supplemental tool holder.

35. In a milling machine, a tool holder, a support for said holder, means for giving said tool holder an oscillatory movement in said support, and means whereby said support is given a rotary oscillatory movement in the oscillatory movement of said tool holder.

40. In a milling machine, a tool holder, means for supporting and guiding said holder, means for giving said tool holder an oscillatory movement in said support and guiding means, and means whereby said first named means may be given a rotary oscillatory movement in the movement of said tool holder therein.

45. In a milling machine, a tool holder, means for supporting and guiding said holder, means for giving said tool holder an oscillatory movement in said support and guiding means, means whereby said first named means may be given a rotary oscillatory movement in the movement of said tool holder therein, and means for giving said tool holder a rotary movement in the aforesaid oscillatory movement.

50. In a milling machine, a tool holder, means for supporting and guiding said holder, and means for giving said tool holder a vertical oscillatory movement in said supporting and guiding means, and for giving said supporting and guiding means a rotary oscillatory movement in the movement of said tool holder therethrough.

55. In a milling machine, a tool holder, means for supporting and guiding said tool holder, means for giving said tool holder a vertical oscillatory movement through said supporting and guiding means and for giving said supporting and guiding means a rotary oscillatory movement, a supplemental tool holder mounted adjacent to said first named tool holder, and means for giving said supplemental tool holder a rotary movement.

60. In a milling machine, the combination with a rotary tool holder and means for rotating the same, of a vertical oscillatory tool holder, means for supporting and guiding said oscillatory tool holder, and means for giving said last named tool holder a vertical oscillatory movement in the supporting and guiding means therefor and for giving said supporting and guiding means a rotary oscillatory movement.

65. In a milling machine, the combination with a rotary tool holder and means for rotating the same, of a vertical oscillatory tool holder, means for supporting and guiding said oscillatory tool holder, means for giving said last named tool holder a vertical oscillatory movement in the supporting and guiding means therefor and for giving said supporting and guiding means a rotary

oscillatory movement, and means for giving said rotary tool holder a vertical and lateral oscillatory movement.

22. In a machine of the class described, 5 a frame; a drive shaft mounted therein, a power shaft geared in connection with said drive shaft, a tool holder, means for guiding said tool holder, and means in operative connection with said power shaft for giving 10 said tool holder an oscillatory movement through said guiding means.

23. In a machine of the class described, a frame, a drive shaft mounted therein, a power shaft geared in connection with said 15 drive shaft, a tool holder, means for guiding said tool holder, means in operative connection with said power shaft for giving said tool holder an oscillatory movement through said guiding means, and means 20 whereby the extent of the oscillatory movement of said tool holder may be varied.

24. In a machine of the class described, a frame, a drive shaft mounted therein, a power shaft geared in connection with said 25 drive shaft, an oscillatory guide mounted in said frame, a tool supporting member slidably mounted in said guide, and means for giving said tool supporting member an oscillatory movement through said guide.

30 25. In a machine of the class described, a frame, a drive shaft mounted therein, a power shaft geared in connection with said

drive shaft, an oscillatory guide mounted in said frame, a tool supporting member slidably mounted in said guide, means for giving 35 said tool supporting member an oscillatory movement through said guide, and means for adjustably connecting a tool with said tool supporting member.

26. In a machine of the class described, a 40 frame, a drive shaft mounted therein, a power shaft geared in connection with said drive shaft by eccentric gears, an oscillatory guide mounted in said frame, a rack construction adjustably connected with one 45 end portion of said power shaft and slidably mounted in said oscillatory guide, and means for adjustably connecting a tool holder with said rack construction.

27. In a milling machine, a rotary oscil- 50 latory head, a tool holder movably mounted in connection with said head, and means for giving said tool holder an oscillatory movement in said head and for oscillating said head.

In testimony that I claim the foregoing as my invention I have signed my name, in presence of the subscribing witnesses, this 31st day of December, 1917.

CHARLES G. FREDMAN.

Witnesses:

C. A. BERGMAN,
H. E. THOMPSON.
